UNITED STATES PATENT OFFICE.

CHARLES L. DU BOIS, OF PORTLAND, OREGON.

HYDRAULIC DOOR-OPENING MECHANISM.

Application filed January 14, 1921. Serial No. 437,248.

To all whom it may concern:

Be it known that I, CHARLES L. DU BOIS, a citizen of the United States, and a resident of the city of Portland, county of Multnomah, and State of Oregon, have invented a certain new and useful Improvement in Hydraulic Door-Opening Mechanism, of which the following is a specification.

My invention relates particularly to garage doors. The main object of my invention is to provide hydraulically operated mechanism, which includes a valve controlled by a key, so that when the bolt of the lock is retracted by the key the valve will be automatically so positioned as to permit the water to flow into the hydraulic cylinder thru the pipe connected with the water main, or with a head of water.

I attain my object by the device and combination of parts illustrated in the accompanying drawings in which;

Fig. 1 shows a diagrammatic plan view of a garage provided with a door having two leaves or double doors which are opened thru the medium of my device;

Fig. 2 shows a fragmentary sectional detail of the operating parts of my invention;

Fig. 3 is a sectional elevation of the key operated valve mechanism located outside of the building, and controlling the admission of water from the main, or head, to the hydraulic cylinder of my device; as the valve is shown in this view it is locked in such position as to drain the water from the hydraulic cylinder into the sewer;

Fig. 4 shows a vertical section similar to Fig. 3, but looking at the opposite side of the parts shown in the latter figure; in this view the valve has been released by withdrawing the bolt of the valve lock by means of the key, thus placing the valve in its open position with the water flowing from the main or head into the hydraulic cylinder and thus operating my device; and

Fig. 5 is a detail of the latching mechanism for locking the door leaves in closed position; the latching mechanism being connected with my device so that it will be released in advance of the action of the hydraulic means for opening the door.

The reference character *a* represents a hydraulic cylinder connected by a pipe *i*, *i'*, with the water main or head. The pipe *i* is led to the outside of the garage, and the flow of water thru the pipe from the head

or main is controlled by a three-way valve *j* which in one position permits the water to flow thru the pipe *i*, *i'*, in the direction indicated by the arrows *z*, *z'* to the hydraulic cylinder and in its other position the valve *j* will close the pipe *i'*, and drain the water from the hydraulic cylinder thru pipe *i* into the sewer thru a pipe *s*.

The valve *j* is operated by spring controlled means which, when unrestrained, place the valve in its position to connect the hydraulic cylinder with the main. These means are detailed in Figs. 3 and 4. They consist of a valve stem *k* forked at its lower end, and provided with a pin *q* bearing in the slot of the valve arm *r* fastened on the projecting end of the valve spindle as at *j'*. On the valve rod *k* is provided a collar *k'* against which bears a coil spring *m* contained in the cylindrical housing *l*; the coil spring tending to lift the valve stem *k* as shown in Fig. 4. The valve stem *k* is provided with a notch *p* which is engaged by the spring bolt *o* of the lock *n*. By depressing the valve stem *k* the bolt *o* of the lock *n* will be caused to be projected into the notch *p* thereby placing and holding the valve *j* in such position as to close the pipe section *i'*, and connect the pipe section *i* with the pipe *s* leading to the sewer.

The valve is located outside of the garage at some convenient place as diagrammatically shown in Fig. 1, and is enclosed by a case *l'* which may be placed under ground as shown in Fig. 4, and on which is mounted the cylinder *l*, the valve stem and its locking mechanism being above ground.

The hydraulic cylinder *a* is fastened to a block *3* which is bolted to any suitable part of the building as at *4*. The piston *b* which reciprocates in the hydraulic cylinder *a* has a stem *c* the free or outer end of which is connected to a cross-head *d* which slides on fixed guide rods *e*. To the opposite ends of the cross-head *d* are pivotally connected rods *f* and *f'* (see Fig. 1) which are connected to the door leaves *g* and *g'* by pins *8*. The forward end of the rod *c* is reduced to receive a collar *c'* and a coil spring *2* is placed on the piston rod *c* between the collar *c'* and the cross-head *d*; the coil spring functioning to take up any sudden jars that occur in the opening and closing of the door. At the farther end *c''* of the piston rod is mounted an upwardly projecting arm *5* clamped

in place by the nuts 6 and 7; the nut 6 being screwed up against the cross-head sufficiently to cause the coil spring 2 to be slightly compressed, and the nut 7 holds the arm 5 firmly against the nut 6.

When water is permitted to enter the hydraulic cylinder from the main thus moving the piston forward and in so doing swinging the two leaves of the door open, the piston 10 rod *c* will finally strike a rubber bumper 14.

The door locking device needs only to be provided for one leaf of the door since it will be impossible to open one door without the other.

15. The door is locked by a latch *w* supported by a bracket 16 from the door frame, (see Fig. 5) engaging with a catch *v* provided on the door leaf *g*. The catch *v* is automatically released by a device fixed to the door 20 frame member 15 and the release of the latch *w* is effected by the forward movement of the cross head *d*, said latch releasing mechanism consisting of a bracket 9 fixed to the rafter 4 and having forked free end 9^a in 25 which is pivoted an arm 10 connected by a rod *x* with the latch *w* which is constructed in the form of the bell-crank as shown in Fig. 5 and the connection being adjustable as shown at *x'* in the latter figure. The 30 forked end 9^a of the bracket 9 also has a pawl 11 made with a shoulder 12 which bears against the arm 10 as shown in Fig. 2. When the cross-head *d* makes its return movement the arm 5 will strike the pawl 11 35 and the passing of the arm by this pawl will cause the latter to rotate on its pivot. The pawl 11 will then resume its pendant position. When my device is operated to open the door the arm 5 carried by the piston rod will strike the pawl 11 correspondingly rotating the latter and causing the 40 pawl 11 to rock the arm 10 and in so doing lifting the latch *w* from its engagement with the catch *v*, hence releasing the door and 45 permitting my device to complete its operation of opening the latter.

All that is required in order to throw my device into action for opening the door is

to insert the key in the lock *n* and retract the spring bolt *o* from the valve rod *k*.

When the door is to be closed the valve *j* is so positioned as to drain the pipe end *i* into the sewer by merely depressing the valve stem *k* and causing it to become engaged with the spring bolt of the lock *n*.

If it is desired to close the doors while in the garage the stop and waste cock 13 may be operated to drain the water from the hydraulic cylinder.

Contemporaneously with the draining of 60 the hydraulic cylinder the weight *t* connected by a cable *u* with a cross-head *d* will operate the latter and the devices therewith connected in such wise as to close the doors, or permit the closing of the latter.

I claim:

1. In a hydraulic door opening device, a hydraulic cylinder and piston therein connected with the door, a connection between the cylinder and a head of water, a valve 70 in said connection controlling the admission, and drainage of the water, into and from, the cylinder, automatic means for positioning the valve to permit the water to flow into the cylinder, means for holding the 75 valve in closed position, a latch for locking the door, and means operatively connected with the piston for releasing the latch when the water pressure moves the piston.

2. In a hydraulic door opening device, a 80 hydraulic cylinder and piston therein connected with the door, a connection between the cylinder and a head of water, a valve in said connection controlling the admission, and drainage of the water into, and from, 85 the cylinder, automatic means for positioning the valve to permit the water to flow into the cylinder, means for holding the valve in closed position, means for automatically retracting the piston when the water is drained from the cylinder, a latch for locking the door, and means operatively connected with the piston for releasing the latch when the water pressure moves the 90 piston.

CHARLES L. DU BOIS.
